UNITED STATES PATENT OFFICE.

WILLIAM HENRY HARRISON, OF PHILADELPHIA, PENNSYLVANIA.

TRAVELING TRUNK.

Application filed February 9, 1924. Serial No. 691,800.

To all whom it may concern:

Be it known that I, WILLIAM HENRY HARRISON, a citizen of the United States, residing in Philadelphia, in the county of Philadelphia and State of Pennsylvania, have invented certain new and useful Improvements in Traveling Trunks, of which the following is a specification.

It is the object of this invention to provide a trunk of such construction which is so equipped that articles of clothing may be so packed therein as to be properly associated to occupy the smallest possible space, to be held securely against displacement, and to be kept free from objectionable creases and wrinkles.

This invention does not relate to what are commonly known as wardrobe-trunks, but to trunks in which the clothing is stored flatwise on the bottom of the trunk beneath a horizontally arranged cover.

In my application for patent filed Feb. 9, 1924, Serial No. 691,801, I have shown a garment hanger of such construction that a suit of men's clothes as well as other articles, such as socks, ties, handkerchiefs, etc., may be associated on the same hanger, hung in a closet or elsewhere when not packed or worn, and held in such condition that these articles while still associated and supported on the hanger, may be transferred quickly and easily to a trunk for traveling purposes.

The invention herein shown, described and claimed relates to the construction of a trunk especially adapted to receive and hold the articles of clothing thus associated and supported, and to the combination of a specially constructed hanger with the new construction of trunk.

As explained in my application for patent above mentioned, the hanger comprises two cross-pieces arranged one above the other and flexibly connected by cordage in such manner as to hold the cross-pieces a short distance apart. The upper cross-piece is provided at opposite ends with knobs which are adapted to engage guides or sockets in a trunk of the construction herein, after more fully described.

According to the invention herein claimed, the trunk is provided at its four corners with vertical guides or sockets adapted to receive the knobs of the hangers and to hold the hangers, with the clothing thereon, against displacement. These guides are of such

construction that a plurality of hangers may be held in each pair of guides and the hangers may be easily placed one above the other in the guides and as readily withdrawn therefrom. A large number of suits or sets of clothes may thus be placed in the trunk and held securely against displacement. In order to hold the hangers and clothes in place when the trunk is not completely filled, I employ a follower consisting of a thin, stout piece of paper-board or wood which is held in place by straps provided with quick-acting buckles.

Preferably sufficient space is provided above the space occupied by the clothes and hangers to accommodate trays adapted to hold small articles of clothing, such as hats, caps, etc. Instead of using a single tray, as usual, I preferably use two trays which are relatively small and light and thus more easily handled. These trays are supported on the tops of the guides or sockets before referred to, and horizontally arranged cleats secured to the front and back walls of the inside of the trunk.

In the accompanying drawings:—

Figure 1 is a perspective view of a traveling trunk embodying my improvements, the lid being partially raised and one of the trays removed.

Figure 2 is a plan view of the trunk body with the lid removed and indicates how clothing is packed therein while supported on hangers.

Figure 3 is a perspective view of a garment hanger of the kind shown, described and claimed in my application for Patent Serial No. 691,801, filed Feb. 9, 1924, and this kind of hanger is employed to support the clothes when being packed.

Figure 3^a is a perspective view, indicating how a suit of clothes may be supported on one of the improved hangers.

Figure 4 is a view similar to Figure 2, showing how the follower is arranged on top of the clothing and held in place by straps having quick-acting buckles.

Figure 5 shows a longitudinal section of the trunk body with the two trays therein, the lid being removed.

Figure 6 is a view on an enlarged scale and in perspective of one corner of the trunk, showing more clearly the construction and arrangement of one of the guides or sockets and indicating how the garment hangers are connected with these guides.

The trunk body A is provided with the usual lid B, and the body and lid are equipped with the usual strengthening and reinforcing devices and suitable locking and fastening members. At the four corners of the trunk there are vertical guides C adapted to receive knobs on the garment hangers of the kind illustrated in Figures 3 and 3^a. Each of these guides extends from the bottom of the trunk vertically to a plane somewhat below the upper edge of the trunk body and on opposite sides of each guide there is a reinforcing cleat or strip D which serves to strengthen the guide and hold it in proper position and to also locate the guide a short distance from the end of the trunk. Preferably each guide is in the form of a metal tube having a vertical slot e, the construction of the four guides being such that the knobs of the hangers may be inserted in the tops of the tubes while the shanks of the knobs enter the slots. In this way horizontal movement of the hangers is prevented.

As before stated, the guides C and strips D terminate below the upper edge of the trunk body, leaving a sufficient space for the accommodation of the trays G. Preferably two trays are used and they are supported partially on the tops of the guides and strips and partially on horizontally arranged cleats E secured to the front and back walls of the trunk body in a horizontal plane coincident with the horizontal plane of the tops of the guides and cleats. These trays may be used to pack hats, caps, and various small articles of clothing, and, being relatively small and light, they may be easily handled.

The follower, hereinbefore referred to, is indicated at H. It may be made of paper-board, wood or other suitable material and is shaped to extend from one end of the trunk to the other and to fit between the guides and cleats. It is loosely contained in the trunk and is held in place when the trunk is tightly packed by straps M having quick-acting buckles m.

The garment hanger, shown in Figures 3 and 3^a, comprises a lower cross-piece N and an upper cross-piece O, which are connected by cordage P and Q, arranged in the manner shown in my application for Patent Serial No. 691,801, filed Feb. 9, 1924. In order to strengthen the upper cross-piece O, I employ a wire R attached at its opposite ends to the cross-piece O and provided with eyes r through which the cordage extends. The upper portion of the cordage P is connected with a hook S which may be detachably connected with the cordage, as shown. At each end of the upper cross-piece O there is a knob o having a shank o' of reduced diameter.

Figure 3^a indicates how a suit of clothes

including a coat, waist-coat, and trousers, may be associated and supported on a single hanger. Two pairs of trousers may, if preferred, be supported on the same hanger and other articles of clothing, such as socks, handkerchiefs, etc., may be also thus supported.

If a traveler has several suits of clothes, each suit being supported on one of the improved hangers, and desires to pack his clothing for traveling purposes, he merely takes down from its support the hangers and suits in succession, and each suit is laid flatwise in the trunk, in the manner indicated in Figure 2. In packing the first suit, the knobs o of the upper cross-piece O of the hanger are inserted in the tops of two guides C, at front and back of the trunk. These knobs can slide easily vertically, the shanks o' of the knobs sliding in the slots e so that horizontal movement of the hanger and clothes is prevented, but the suit can be lowered without being folded and deposited on the bottom of the trunk. The next suit of clothes is inserted in the trunk in a similar way, the upper cross-piece O being connected with the vertical guides C at the opposite end of the trunk, as indicated in Figure 2. A plurality of suits may thus be packed, each suit being laid flatwise, one above the other, without changing the natural creases and without producing additional creases or wrinkles. When the trunk is completely filled, the follower H is placed on the topmost suit and the straps M are applied and fastened securely. When this is done there is no possible danger of the hangers and clothing being displaced. When arriving at the destination of the traveler the follower H may be withdrawn and the suits of clothes on their hangers successively removed and hung up in a closet or elsewhere for future use.

As before stated I preferably employ two short trays instead of a single long one, and it will be observed that each tray G is supported at one end on the tops of the guides C and cleats D and at its inner end each tray is supported on the cleats E. It is not essential, however, so far as part of my invention is concerned whether trays are used at all or whether a plurality of trays or only one is used.

The guides C being held by the cleats or strips D a short distance from the ends of the trunk, sufficient space is provided to accommodate those portions of the trousers extending across the upper cross-piece of the hanger as well as those parts of the cordage disposed above the cross-piece.

The knobs on the ends of the garment hangers, while free to move vertically in the slotted tubes or guides while packing or unpacking, effectually prevent the hangers from being displaced when the trunk is

packed. The lowermost hangers rest on the bottom of the trunk and the trays rest on the tops of the tubes so that there can be no escape of the hangers from the guides when the trunk is closed.

I claim as my invention:

1. A traveling trunk having within it on opposite sides, open ended vertical guides which are shaped to receive and retain the ends of cross bars of garment hangers at the four corners of the trunk, the guides on one side cooperating with the guides on the opposite side to hold said cross bars in position.
- 15 2. A traveling trunk having within it on opposite sides at the four corners open ended vertical slotted guides which are shaped to receive and retain the headed ends of the cross bars of garment hangers, the guides on the front side of the trunk being so placed as to cooperate with the guides on the rear side of the trunk in holding the cross bars of the hangers from moving sidewise within the trunk.

3. A traveling trunk having within it at 25 two of its corners vertical guides adapted to receive the opposite ends of a plurality of garment hangers and which are reinforced and held away from the ends of the trunk by vertically arranged cleats.

30 4. A traveling trunk provided with removable trays and having within it at its four corners vertical guides for garment hangers which extend part way to the upper edge of the trunk body, said trunk being 35 provided also with horizontally arranged cleats which serve to support the inner ends of the trays, the outer ends of which are supported on the tops of the guides.

5. A traveling trunk having within it at 40 its four corners vertical slotted guides in combination with garment hangers having cross pieces provided with knobs fitting the guides and trays resting on the guides and closing their upper ends.

45 In testimony whereof, I have hereunto subscribed my name.

WILLIAM HENRY HARRISON.
